(57) **CLAIM**

The ornamental design for an endobronchial blocker, as shown and described.

DESCRIPTION

FIG. 1 is a perspective view of a first embodiment of the endobronchial blocker of my design;

FIG. 2 is a side view of the first embodiment of the endobronchial blocker of my design;

FIG. 3 is an end view of the first embodiment of the endobronchial blocker of my design;

FIG. 4 is an end view of the first embodiment of the endobronchial blocker of my design, taken from the opposite end of that shown in FIG. 3;

FIG. 5 is a perspective view of a second embodiment of the endobronchial blocker of my design;

FIG. 6 is a side view of the second embodiment of the endobronchial blocker of my design;

FIG. 7 is an end view of the second embodiment of the endobronchial blocker of my design;

FIG. 8 is an end view of the second embodiment of the endobronchial blocker of my design, taken from the opposite end of that shown in FIG. 7;

FIG. 9 is a perspective view of a third embodiment of the endobronchial blocker of my design;

FIG. 10 is a side view of the third embodiment of the endobronchial blocker of my design;

FIG. 11 is an end view of the third embodiment of the endobronchial blocker of my design;

FIG. 12 is an end view of the third embodiment of the endobronchial blocker of my design, taken from the opposite end of that shown in FIG. 11;

FIG. 13 is a perspective view of a fourth embodiment of the endobronchial blocker of my design;

FIG. 14 is a side view of the fourth embodiment of the endobronchial blocker of my design;

FIG. 15 is an end view of the fourth embodiment of the endobronchial blocker of my design; and,

FIG. 16 is an end view of the fourth embodiment of the endobronchial blocker of my design, taken from the opposite end of that shown in FIG. 15.
